(57) **CLAIM**

The ornamental design for an “air freshener for an automobile”, as shown and described.

DESCRIPTION

FIG. 1 is a front elevational view of “air freshener for an automobile”, showing our new design;

FIG. 2 is a right side elevational view thereof;

FIG. 3 is a left side elevational view thereof;

FIG. 4 is a rear elevational view thereof;

FIG. 5 is a top view thereof; and,

FIG. 6 is a bottom view thereof.

The broken line showing of environmental structure in FIGS. 1 to 2 is for illustrative purposes only and forms no part of the claimed design.
